(57) **CLAIM**

The ornamental design for a binocular, as shown and described.

DESCRIPTION

The patent or application file contains at least one drawing executed in color. Copies of this patent or patent application publication with color drawing(s) will be provided by the Office upon request and payment of the necessary fee.

FIG. 1 is a first perspective view of a first embodiment of the binocular of our new design;

FIG. 2 is a second perspective view of the binocular of FIG. 1;

FIG. 3 is a front elevation view of the binocular of FIG. 1;

FIG. 4 is a rear elevation view of the binocular of FIG. 1;

FIG. 5 is a top plan view of the binocular of FIG. 1;

FIG. 6 is a bottom plan view of the binocular of FIG. 1;

FIG. 7 is a right side elevation view of the binocular of FIG. 1;

FIG. 8 is a left side elevation view of the binocular of FIG. 1;

FIG. 9 is a first perspective view of a second embodiment of the binocular of our new design;

FIG. 10 is a second perspective view of the binocular of FIG. 9;

FIG. 11 is a front elevation view of the binocular of FIG. 9;

FIG. 12 is a rear elevation view of the binocular of FIG. 9;

FIG. 13 is a top plan view of the binocular of FIG. 9;

FIG. 14 is a bottom plan view of the binocular of FIG. 9;

FIG. 15 is a right side elevation view of the binocular of FIG. 9; and,

FIG. 16 is a left side elevation view of the binocular of FIG. 9.

The broken lines in FIG. 6 depict a portion of the binocular that forms no part of the claimed design.

UNITED STATES PATENT AND TRADEMARK OFFICE
CERTIFICATE OF CORRECTION

PATENT NO. : D867,416 S
APPLICATION NO. : 29/610324
DATED : November 19, 2019
INVENTOR(S) : N. Radau et al.

Page 1 of 1

It is certified that error appears in the above-identified patent and that said Letters Patent is hereby corrected as shown below:

On the Title Page

On Page 2:

Under (56) Foreign Patent Documents Line 19: delete “CN 200130222190.9” and substitute -- CN 201130222190.9 -- therefor.

Under (56) Foreign Patent Documents Line 20: delete “CN 201630026174.5 7/2016” and substitute -- CN 201630026174.5 8/2016 -- therefor.

Signed and Sealed this
Twenty-fourth Day of December, 2019

Andrei Iancu
Director of the United States Patent and Trademark Office
